JOHN BRITTON FALLOURE AND LESLIE MARSHALL ENGLISH, OF WHEELING, WEST VIRGINIA.

PUMP.

No. 804,834.

Specification of Letters Patent.

Patented Nov. 21, 1905.

Application filed February 15, 1905. Serial No. 245,692.

To all whom it may concern:

Be it known that we, JOHN BRITTON FALLOURE and LESLIE MARSHALL ENGLISH, citizens of the United States, residing at Wheeling, in the county of Ohio and State of West Virginia, have invented new and useful Improvements in Pumps, of which the following is a specification.

This invention relates especially to pumps for deep wells, such as oil-wells, and has reference to that type of pump employing a rigid pump-rod.

The primary object of the invention is an improved construction of this type of pump whereby the sucker may be removed and replaced without removing the pump-rod, and, furthermore, it is the object to provide for the application of the invention to deep-well pumps now in use and without disturbing the stationary parts thereof.

A further object of the invention is to overcome the bending and yielding of the pump-rods of deep-well pumps, and thereby prevent the lessening of the stroke of the sucker, which is due to this cause.

The invention consists in forming the pump-rod hollow or tubular, so as to admit of the passage therethrough of the sucker, and in providing means whereby the sucker is adapted to be secured to and released from the pump-rod and raised therethrough.

The invention further consists in other novel features in the construction and arrangement of parts, all as hereinafter described and specifically set forth in the appended claims.

In the accompanying drawings, Figure 1 is a vertical section taken through the complete pumping apparatus and showing the hollow pumping-rod and sucker in operative position thereon. Fig. 2 is a vertical section showing a portion of the pump-tube and suction-barrel and also showing the pump-rod and sucker with its associated elements in the position necessary to effect the withdrawal of the sucker.

Fig. 3 is a horizontal section taken on the line 3-3 of Fig. 1. Fig. 4 is an edge view of the frame-section forming an extension of the sucker-rod, in which is carried the stops for engaging the pump-rod.

The invention is illustrated in its application to the pumps of oil-wells, and in the drawings 1 designates the well-casing, and 2 the pump-casing or tube, the latter being provided at its lower end with the pump-barrel 3, having

the usual foot or check valve 4. This pump-barrel is formed after the manner of those now in use, having the suction-bore 5 thereof flared at the top to present inclined walls 6 to facilitate the entrance of the sucker 7, which walls terminate in an annular shoulder or seat 8, as it has been the purpose of the invention to utilize this form of construction in the manner to be clearly explained in order to make ready adaptation of the invention to pumps already installed and without removing the pump-tube and its connected parts. As is usual, the pump-tube is provided with a cap 9, which forms the guide to the rod 10 that connects the pump-rod 11 with the pump-beam 12.

In the present instance the pump-rod 11 is tubular and of such size as to approximately fill the pump-tube and be guided in its movement and maintained against bending, this latter tendency being greatly overcome by the increased diameter of the rod. The bore of the pump-rod compensates for the space occupied by the rod in the pump-tube by being kept in open relation at all times with the surrounding water-space, thus providing free passage of the water up through the pump-rod and out at the openings 13 or through any other suitable exit.

The bore of the pump-rod 11 in the present instance is of a size to readily admit the passage therethrough of the sucker 7 and its sucker-rod 14, the latter being connected with a cable 15, by which it and the sucker are suspended from the top of the well and by means of which cable these parts are removed from the pump-tube. The sucker-rod includes an extension-frame 14^a, (shown detached in Fig. 4,) which extension comprises two parallel strips 14^b, secured together in spaced relation and forming, primarily, a nest or recess 16, in which is pivotally secured two folding plates 17, which extend in opposite directions and form a stop or abutment to engage the lower end of the pump-rod when the sucker is in its normal position thereon, as shown in Fig. 1, and in this position the sucker-rod is maintained by the cable 15, which is not only the means for raising and lowering the sucker, but the attaching means as well, and is connected to the pump-rod at the upper end thereof or, as shown, to the pump-beam in order that the cable and pump-rod will move together when in their assembled relations. In connecting the cable, as shown, the rod 10 is

made tubular to admit the cable, and in order to provide for the adjustment of the cable it is attached to a screw-threaded hook 18, supported in the adjusting-nut 19 on the beam 12 or in any other suitable manner.

The folding stops 17 are each formed so as to present an upwardly-flaring edge 17^a from the under side thereof, providing thereby guiding edges which contact with the sides of the tubular pump-rod 11 and prevent any binding thereof within the rod during its passage therethrough in either direction. When within the pump-rod, the stop 17 will confine and clamp the spring 20 after the manner shown in Fig. 2, and upon passing out of the pump-rod they will be forced apart by the tension of said springs and will assume their horizontal position, (shown in Fig. 1,) in which they rest upon the base of the recess in which they are mounted.

In Fig. 1 the pump-rod 11 is shown raised to the limit of its upward pumping stroke; but in making the application the pump-rod is maintained a sufficient distance above the limit of its upward stroke to bring the stops 17 far enough below the lower end of the rod to admit of the extension of the stops into their operative position, whereupon they are brought against the pump-rod by the lowering of said rod, and the cable is then made secure to maintain its combined operative relation.

For the removal of the sucker the cable 15 is lowered to the point shown in Fig. 2, in which the stops 17 are folded, as shown in said figure, by contact of their guiding edges 17^a with the wall of the mouth of the suction-barrel 3, which is formed as in the general construction of pumps with a tapering wall 6.

With the stops nested, as shown in Fig. 2, by engagement with the wall 6, the pump-rod 11 is brought to rest at the limit of its downward stroke, and preferably, as shown, upon the shoulder or seat 8, the beveled edge 6^a facilitating the guiding of the rod to its seat. This action brings the stops 17 within the pump-rod and the sucker, and its associated parts can then be drawn up through the rod by the cable and removed from the rod upon removing its end cap or coupling 11^a and the cap 9 of the pump-tube.

What we claim, and desire to secure by Letters Patent, is—

1. In a pump, the combination with the pump-tube, of a hollow pump-rod therein, and a sucker adapted to be maintained in operative relation to said rod and be raised and lowered therethrough, substantially as and for the purpose set forth.

2. In a pump, the combination with the pump-tube, of a hollow pump-rod therein, a sucker adapted to pass through said rod, and means for raising and lowering the same, substantially as and for the purpose set forth.

3. In a pump, the combination with the

pump-tube, of a hollow pump-rod therein, a sucker adapted to pass through said rod, means for raising and lowering the sucker, and means for maintaining the sucker in operative relation to said rod, substantially as and for the purpose set forth.

4. In a pump, the combination with the pump-tube and its sucker, of a hollow pump-rod for the sucker, said rod being in open relation to the interior of the pump-tube, substantially as and for the purpose set forth.

5. In a pump, the combination with the pump-tube and its sucker, of a pump-rod tube within the pump-tube and in close spaced relation thereto, said pump-rod tube being in open relation to the pump-tube, substantially as and for the purpose set forth.

6. In a pump, the combination with the pump-tube, of a hollow pump-rod therein, a sucker adapted to pass through said rod, means for raising and lowering the sucker, stops associated with the sucker and adapted to be projected into engagement with the lower end of the pump-rod, and means for nesting the stops to permit their passage up through the pump-rod, substantially as and for the purpose set forth.

7. In a pump, the combination with the pump-tube, of a hollow pump-rod therein, a sucker adapted to pass through said rod, a sucker-rod for co-operation with the lower end of said pump-rod, stops adapted to project from the sucker-rod and engage the lower end of the pump-rod, and means for maintaining said stop in said engagement, substantially as and for the purpose set forth.

8. In a pump, the combination with the pump-tube, of a hollow pump-rod therein, a sucker adapted to pass through said rod, means for suspending the sucker from the top of the pump, the same having movement with the pump-rod, means associated with the sucker, adapted to be nested to pass within the pump-rod and projected upon emergence therefrom to engage the lower end of said rod, and means for nesting said rod-engaging means, substantially as and for the purpose set forth.

9. In a pump, the combination with the pump-tube and its barrel, of a hollow pump-rod therein, the sucker adapted to pass through said rod, means extending therefrom for suspending the sucker from the top of the pump, the same being adapted to move with the pump-rod during the pumping operation, automatically-projectable stops for engagement with the lower end of the pump-rod, said stops being adapted to be nested by engagement with a contracted portion of the pump-tube, substantially as and for the purpose set forth.

10. In a pump, the combination with the pump-tube, of a hollow pump-rod therein, a sucker, having a sucker-rod adapted to extend within said pump-rod and in normally operative position, said sucker and sucker-rod adapted to pass through said pump-rod, means

carried by the sucker-rod for automatically engaging and disengaging the lower end of the pump-rod as the sucker-rod is raised and lowered, and means for raising and lowering the 5 sucker-rod and maintaining the same in engaged position on the pump-rod, substantially as and for the purpose set forth.

11. In a pump, the combination with the pump-tube and its suction-barrel, a hollow 10 pump-rod therein, a sucker, a sucker-rod, projectable means carried by the sucker-rod for engaging the pump-rod at its lower end and adapted to be retracted so as to pass through said pump-rod, means for lowering the sucker

15 and sucker-rod independently of the pump-rod and an abutment for engaging the said projectable means to retract the same, substantially as and for the purpose set forth.

12. In a pump, the combination with the 20 pump-tube and its suction-barrel, a hollow pump-rod therein, a sucker, means for raising and lowering the same through said rod and adapted for movement with said rod, foldable stops carried by said means for engaging

25 the lower end of the pump-rod, and adapted to fold by engagement with the mouth of the suction-barrel and project within the pump-rod tube upon the same being lowered to receive them, substantially as and for the pur-

30 pose set forth.

13. In a pump, the combination with the pump-tube, of a hollow pump-rod adapted to be raised and lowered beyond the limits of its stroke, a sucker adapted to pass through said rod, means for raising and lowering the sucker, 35 foldable stops carried by said means for engaging the lower end of the pump-rod, said stops being located above the sucker a distance equal to its stroke, and adapted to enter the mouth of the suction-barrel to fold the 40 same when the sucker is lowered below the normal limit of its stroke, substantially as and for the purpose set forth.

14. In a pump, the combination with the pump-tube, of a hollow pump-rod, a sucker 45 adapted to pass through said rod, means for raising and lowering the sucker, pivoted stops carried by said means, means for bringing said stops into a position to pass through said pump-rod, and a spring or springs for actuating 50 said stops when released from their nested positions, substantially as and for the purpose set forth.

In testimony whereof we affix our signatures in presence of two subscribing witnesses.
